CLAIM

The ornamental design for a hair growth stimulator, as shown and described.

DESCRIPTION

1. Hair growth stimulator

1.1 : Perspective

1.2 : Perspective

1.3 : Front

1.4 : Right

1.5 : Back

1.6 : Perspective

1.7 : Front

Reproduction 1.1 shows the hair growth stimulator in an environment. Reproduction 1.6 shows the hair growth stimulator in an alternate configuration of length; Reproduction 1.7 shows the hair growth stimulator in an alternate configuration of width.

In Reproduction 1.2, the broken lines are for the purpose of illustrating environment only and form no part of the claimed design.
